APPARATUS FOR CLEANING SEDIMENTATION TANKS

William C. Laughlin, Kew Gardens, and Abraham B. Asch, Brooklyn, N. Y., assignors, by mesne assignments, to Filtration Equipment Corporation, New York, N. Y., a corporation of Delaware

Application November 23, 1932, Serial No. 644,020

6 Claims. (Cl. 210—3)

This invention relates to sedimentation systems and more particularly to apparatus for use in moving settled solids and sludge longitudinally of the settling tank.

The invention has for its object the provision of a self-propelling mechanism for traveling longitudinally of the tank containing the sewage liquid, and it involves instrumentalities by means of which at the opposite terminals of movement to effect an automatic reversal in the direction of travel so that the mechanism will travel continuously in forward and backward directions longitudinally of the tank, being for such purpose automatically reversed at each terminal of movement.

Another object of the invention is the provision of a novel sweeping or scraping device which is moved longitudinally of the tank by the traveling mechanism, and this sweeping or scraper device, in furtherance of the object of the invention, is constructed and arranged for reversing operations so that the sweeping or scraping operation longitudinally of the tank will take place in one direction only.

A further object of the invention is to provide means whereby automatically to effect the reversing operation of the sweeping or scraping device and further to so control and correlate the reversing operation of the traveling mechanism and sweeping device that these parts at the terminals of movement will be automatically reversed in proper timed relation for carrying out their respective functions in an efficient manner.

Still a further object of the invention is the provision of a sweeping device of the character described which will effectually remove solid matter and sludge from rounded corners.

With the foregoing and other objects in view, the invention consists in the construction and relative arrangement of parts so combined as to coact and cooperate with each other in the performance of the functions and the accomplishment of the results herein contemplated and comprises in its evolution the simple and practical example illustrated in the accompanying drawings, wherein similar reference characters designate corresponding parts throughout the several views, and in which:—

Figure 1 represents a fragmentary top plan view of a settling tank embodying the present invention;

Fig. 2 is a longitudinal sectional view, taken on the line 2—2 of Fig. 1, looking in the direction of the arrows associated with said line;

Fig. 3 is a vertical cross sectional view and ele-

vation, this view being taken on the line 3—3 of Fig. 1, looking in the direction of the arrows associated with said line;

Fig. 4 is an enlarged detail sectional view and elevation, taken on the line 4—4 of Fig. 1 and disclosing the arrangement of parts whereby the reversing operations are effected; and

Fig. 5 represents a top plan view and section, taken on the line 5—5 of Fig. 4, with parts broken away.

Referring now with more particularity to the accompanying drawings, 10 denotes a sedimentation tank, herein shown as built from concrete, although manifestly it may be constructed of any known or approved material. This tank is of 15 elongated rectangular form comprising opposite side walls 11, 12, opposite end walls 13, 14, and a bottom 15. Adjacent the end wall 13, which may be conveniently referred to as the forward or intake end of the tank, the bottom 15 is provided 20 with a sump 16 in which the solid matter, sediment and sludge, swept or scraped from the bottom 15, may be collected. For the withdrawal of the refuse collected in the sump 16, suitable suction pipes 17 may be provided. The tank may be 25 furnished with an inlet conduit 18 through which the sewage liquids or wastes may be introduced into the tank for treatment. The tank is also herein represented as provided with exterior launders 19, 19' which extend respectively along 30 the side walls 11 and 12 and are sloped towards the rear of the tank so as to feed into a discharge launder 20. The side walls 11 and 12, near their top edges may be provided with spaced apart outlet openings 21 through which the clear liquor, 35 rising upwardly towards the open top of the tank, may flow outwardly for discharge into the exterior launders.

The traveling mechanism comprises a carriage including suitable skeleton framework 22 40 of a length to extend transversely of the tank, as shown in Figs. 1, 2 and 3. This framework may be constructed in any manner suitable for carrying the various parts hereinafter described and it is suitably mounted upon track wheels 45 23 of which in the present embodiment there are two at each end of the frame. In the present instance, the track wheels are represented as fixed to axles 24 mounted to turn in suitable bearings provided in the framework. These track 50 wheels turn upon track rails 25 suitably mounted upon the top edges of the parallel side walls 11 and 12. These track rails extend substantially the full length of the tank so that the carriage may travel substantially the full length 55

thereof in order that the desired sweeping and scraping operations may be effected. Each track rail, at its opposite ends, may be provided with suitable upstanding stops 26 at or near the terminals of movement of the carriage.

The carriage is caused to travel by applying power to one of the axles 24; and the motive power for this purpose comprises an electric motor 27 mounted upon a platform 28 suitably provided on the carriage. Motion may be transmitted from the motor to the axle by any suitable transmission, and in the present instance suitable reduction gears contained within a reduction gear box 29 are operated from the motor, there being a shaft 30 driven by the reduction gears and carrying a wheel 31 which is in driving engagement with a wheel 32 fixed to one of the axles 24. The electric motor may be of the reversible type, supplied with electrical energy through a three-phase system 33 the individual wires of which are connected with corresponding brushes 34 carried by (but suitably insulated from) a support 35 depending from the carriage framework adjacent the inner face of the side wall 12. These brushes engage bus bars 36 mounted on suitable insulation 37 fixed to the inner face of the side wall 12 at the top end thereof above the outlet openings 21. Included in the three-phase circuit 33 is a reversing switch 38 having an actuating lever 39 whereby to be operated.

The sweeping or scraping device of our invention depends within the tank from the overhead carriage and includes a pendent skeleton framework comprising parallel oppositely disposed V-shaped frames 40 and a horizontal shaft 41 which rigidly connects the apex of one frame with the apex of the other. Swingably mounted upon the horizontal shaft 41 between the V-shaped frames 40 is a skeleton framework comprising parallel, oppositely disposed bars 42, 42, the same being swingably mounted intermediate their ends upon said horizontal shaft 41. Fixed to the lower ends of these bars 42, 42 is a scraper plate or board 43 having a length substantially equal to the interior cross dimension of the tank but nevertheless leaving suitable clearance spaces 44 between its opposite ends and the inner faces of the side walls. The parallel bars 42 may be connected with one another by any suitable strengthening members, as for instance, by cross members 45 and 46; and the scraping plate or board 43 may be reinforced by suitable obliquely inclined brace bars 47 which extend downwardly and outwardly from the bars 42 to positions adjacent the outer extremities of the scraper plate, as shown in Fig. 3. For the purpose of counterbalancing the scraper plate or board 43, a suitable counterweight 48 is secured to and between the opposite ends of the bars 42.

The means whereby to operate the swingable frame includes a short arm 49 which projects from one of the bars 42, and a connecting bar 50 the lower end of which is pivoted at 51 to the outer end of said short arm 49 while its upper end is pivoted at 52 to a rotatable disk member 53 upon the carriage. As clearly illustrated in Fig. 5, the disk member 53 is secured to a stud shaft 54 mounted for rotation in a bearing 55, provided for the purpose on the carriage framework. Said rotary stud shaft 54 also has fixed thereto a gear 56 in mesh with a large gear 57 fast on a shaft 58, suitably mounted for rotation in bearings 59 and 60 provided

for the purpose on the carriage framework. In this arrangement, the parallel shafts 54 and 58 extend transversely of the tank and in such position that the shaft 58 will come in close adjacency to the reversing switch lever 39 and this shaft after passing through its bearing 60 is provided in a plane paralleling the outer face of the side wall 12 with a lateral contact arm 61.

Referring to Fig. 2, it will be seen from the full line illustration of the sweeping device, that when the swing frame is in perpendicular or substantially perpendicular position so as to sweep material forwardly for collection in the sump when the carriage moves forwardly or toward the end wall 13, the pivotal connection 18 between the rod 50 and disk member 53 will be in an off-center position with an abutment shoulder 62 of the disk engaging a stop 63. With these parts in this relation, the swing frame will be blocked against reverse movement under the force which it must exert in sweeping refuse toward the sump. Moreover, with the parts in this relationship, the lateral contact arm 61 will incline downwardly and forwardly in a position to impinge a stop roller 64 supported on a bracket 65 fixed to the side wall 12. Said stop roller 64 is located at or near the forward terminal of movement of the carriage and when it is engaged by the contact arm 61 under forward movement of the carriage, the wheel 57 will be moved in the direction indicated by the arrow 66 with the result that the disk 53 will be moved in the direction indicated by the arrow 67 until a shoulder abutment 68 contacts with the stop pin 63. Under this operation, the parts will be caused to assume the respective positions indicated by the dot-dash lines at the left-hand end of Fig. 2, when the swing frame will have been swung into an oblique, elevated position.

The reversing switch lever 39 is provided with a roller 69 which turns on a cam 70 fixed to the shaft 58. During the turning of the shaft 58, brought about by the engagement of the contact arm 61 with the stop roller 64 under the forward travel of the carriage, said lever 39 will be actuated in a manner to reverse the switch 38 and hence effect a reversal of the motor 27, whereupon the carriage will be propelled in the opposite direction, that is to say, toward the rear end 14 of the tank. It will be appreciated that in this arrangement, the swing frame, having been elevated, will remain in its elevated position during the return or backward travel of the carriage, due to the pivotal connection at 52 being in an off-center position so that any motion of the scraper will only tend to jam the disk member 53 harder against stop 63, with the result that there will be no sweeping or scraping of the settling during such return or backward travel of the carriage. At or near the rear terminal of movement of the carriage, there is provided a roller stop 71 supported upon a bracket 71' and when the contact arm 61 during return travel of the carriage, impinges this roller 71, the wheel 57 will be moved in the direction indicated by the arrow 72 with the result that the disk 53 will be moved in the direction indicated by the arrow 73 until the shoulder abutment 62 engages the stop 63, thereby again moving the swing frame into perpendicular or substantially perpendicular position. As will be noted in Fig. 2, the inner corner between the rear wall 14 and bottom 15 may be so rounded as indicated at 74 that the swing frame in moving from its ele-

vated position to its perpendicular position will carry the scraper plate 43 in such close relationship to the concavely rounded corner 14, that any settling upon such rounded corner will be removed therefrom. It will of course be recognized that when the contact arm 61 is moved by reason of its impingement against the rear stop roller 71, the shaft 58 will turn in a direction for so actuating the lever 39 that the motor 27 will be reversed at this terminal of movement in order that the carriage may again travel forwardly toward the end 13 of the tank.

The specific manner in which, or by means of which, the frame for carrying the scraper is supported by the carriage is not so important, for many different specific means can be devised for this purpose, but in any case it is characteristic for the purpose and object of our invention that this frame be elevated from sweeping or scraping position when the reverse or backward movement of the carriage takes place, and further that means be provided at each terminal of movement for reversing the motor as well as the swing carriage in order to provide for continuous operation of the carriage forward and backward along the length of the tank.

While our invention has been illustrated and described with some degree of particularity, it will be recognized that in practice various changes and illustrations may be made therein, and further that the invention is capable of embodiment in many different types of sewage tanks, settling basins and the like. It has been sought herein to illustrate only such an embodiment as will suffice to exhibit the character of the invention. Reservation is, therefore, made to the right and privilege of changing the form of the details of construction or otherwise altering the arrangement of the parts without departing from the spirit or scope of the invention or the scope of the appended claims.

We claim:

1. In a sedimentation system, the combination with a sewage settling chamber, of self-imelled reversible mechanism adapted to travel longitudinally of said chamber in either direction, a frame supported by said mechanism, a scraper device mounted on a fixed axis on said frame for rotation and adapted when rotated into one position to sweep the bottom of said chamber, reversing means, means under the control of said reversing means for reversing the direction of travel of said mechanism at its terminals of movement, and means under the control of said reversing means for automatically rotating said scraper device to a position in which it is ineffective to sweep the bottom of said chamber.
2. In an improved sweeping apparatus, the combination of a frame, a member pivotally attached thereto between its ends for rotation in a vertical plane, a scraping plate fixed to one

end of said member and a counterweight applied to the opposite end thereof, a rotating wheel and means for rotating the same in either direction, a pitman bar and crank connection between said wheel and member whereby to rotate the latter from the former, and means co-operating with said wheel for limiting the rotation of the same in both directions.

3. In an improved sweeping apparatus, the combination of a frame, a member pivotally attached thereto between its ends for rotation in a vertical plane, a sweeping device attached to one end of said member and a counterweight applied to the opposite end thereof, a rotary wheel on the frame and a connecting bar pivotally connecting said wheel with said member.

4. In scraper operating mechanism including a tiltable scraper, the combination with a controlling arm for the scraper, of a rotatable member to which said arm is pivotally attached at one end, said member being provided with spaced shoulder abutments at one side of a diametrical center line thereof, and a stop for engagement by said abutments in off-center positions.

5. In scraper operating mechanism including a tiltable scraper, the combination with a controlling arm for the scraper, of a rotatable member to which said arm is pivotally attached at one end, said member being provided with spaced shoulder abutments at one side of a diametrical center line thereof, a stop for engagement by said abutments in off-center positions, and means associated with said member for operating the same a distance sufficient to bring either shoulder into engagement with said stop.

6. In a cleaning apparatus for a sewage tank including a traveling carriage adapted to travel longitudinally of the tank, a rigid frame projecting downwardly therefrom into the tank, a shaft supported in the lower portion of said frame, a member mounted intermediate its ends on said shaft to swing thereon and carrying a scraping plate at one end and a counterweight on the opposite end, said member being swingable to and from a position in which the scraping plate will sweep settled solids along the bottom of the tank during the travel of the carriage, a reversing member and its actuating means on the carriage and a connection between said reversing member and swingable member for rotating the latter from the operation of the former, said reversing member, actuating means and connection between the reversing member and swingable member so arranged as to bring the scraping plate into position for sweeping action when the carriage moves in one direction and to rotate the sweeping plate to a position in which it will be out of sweeping relation with respect to the bottom when the carriage moves in a reverse direction.

WILLIAM C. LAUGHLIN.
